Inventor,

Masachii Miyahara

UNITED STATES PATENT OFFICE.

MASAICHI MIYAHARA, OF LOS ANGELES, CALIFORNIA.

DESIGN FOR A BATH-TUB.

51,506.

Specification for Design.

Patented Nov. 20, 1917.

Application filed August 9, 1917. Serial No. 185,361. Term of patent 7 years.

To all whom it may concern:

Be it known that I, MASAICHI MIYAHARA, a subject of the Emperor of Japan, residing at Los Angeles, in the county of Los Angeles and State of California, have invented a new, original, and ornamental Design for a Bath-Tub, of which the following is a specification, reference being had to the accompanying drawing, forming part thereof.

In the drawing:

Fig. 2 is a top plan view thereof.

I claim:

The ornamental design for a bath tub, as shown.

In testimony whereof, I hereunto affix my signature this 2nd day of August, 1917.

MASAICHI MIYAHARA.

Witnesses:

EDWARD M. KOJIMA,
H. K. FUNAKASKI.
